TOY

Walter J. Wieczorek, Battle Creek, Mich.

Application February 15, 1936, Serial No. 64,148

1 Claim. (Cl. 272—53)

The present invention relates to a toy and has for its prime object to provide a toy of the mobile type on which a child may sit and by a hopping motion may cause the propulsion of the toy and himself from place to place.

Another important object of the invention resides in the provision of a toy of this nature which is simple in its construction, inexpensive to manufacture, strong and durable, easy to manipulate, 10 amusing, affording exercise, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:—

Figure 1 is a side elevation of a toy embodying the features of my invention.

Figure 2 is a top plan view thereof.

Figure 3 is a vertical central section taken substantially on the line 3—3 of Figure 2.

Figure 4 is a bottom plan view of the toy.

Figure 5 is a view similar to Figure 3 showing the parts in a different position.

Figure 6 is a front elevation of the toy.

Figure 7 is a perspective view of the front rock-30 er foot.

Referring to the drawings in detail it will be seen that the numeral 5 denotes a seat the rear portion of which is relatively broad with respect to the front portion thereof. Rising from the front portion is a handle post 6 with a handle cross-head 7 on the upper end thereof. Under the rear or broader portion of the seat 5 is a plate 8. A pair of hinges 9 is fixed to the plate and to a cross bar 10 fixed to a pair of legs 11 on the lower ends of which are fixed elongated rocker feet 12. A spring 14 is fixed to the cross bar 10 as at 15 and under the seat 5 as at 16, to urge the rear rocker structure normally forwardly to the position shown in Figure 3.

A forward rocker structure includes a plate 17 having a hinge 18 secured thereto and also secured to a cross member 19 from which depends a leg 20 on the lower end of which is fixed a rocker shoe 21 broader than the rocker shoes 12 and having a foot rod 23 extending thereacross and out beyond the sides thereof as shown to advantage in Figure 7.

The hinges 9 and 18 are secured in place by the bolts 22, on which are threaded the conventional retaining nuts. These bolts extend a short

distance beyond the head of the retaining nuts to limit the forward and rearward movements of the legs 20 and 11 respectively. Figure 5 illustrates the leg 11 being limited in its rearward movement by the bolts 22.

It will also be understood that the hinges 9 and 18 constitute important elements of my invention, when it is stated that they assure the front leg 20 locking at a ninety degree angle and the locking pressure of both front leg and rear legs being upward. This upward locking pressure with the front leg locking at a ninety degree angle gives the rider of the toy a faster ride than would otherwise be the case and also affords a more buoyant ride with a minimum amount of effort on the part of the rider. Incidental to the use of the toy the rider presses downwardly on the footrests afforded by the cross rod 23, relax and move forwardly and press the front leg again, and this without back and forward swaying of the body.

As shown in Figures 1 and 3, the child seated on the toy with his or her feet resting on the foot rod 23, the child tilts backwardly and throws the shoe 21 forwardly and then tilts forwardly, see Figure 5, and the spring 14 will move up the rear shoes 12. In this way a mobile action is attained giving the child considerable exercise and amusement.

It is thought that the construction, operation, utility and advantages of this invention will now be quite apparent to those skilled in this without a more detailed description thereof.

The present embodiment of the invention has been described in considerable detail merely for the purposes of exemplification since in actual practice it attains the features of advantage enumerated as desirable in the statement of the invention.

It will be apparent that changes in the details of construction, and in the combination and arrangement of parts may be resorted to without departing from the spirit or scope of the invention as hereinafter claimed or sacrificing any of its advantages.

What is claimed is:—

In a toy of the kind described, a seat having a forward portion of reduced width, a handle fixed to and rising from said forward portion, a pair of spaced rear legs having at their lower ends longitudinally disposed parallel rocker feet, a cross-bar fixed to and connecting the upper ends of said legs, spaced hinges having leaves connected to the underside of the rear portion of the seat and also having pendent leaves opposed

and connected to the rear side of said cross-bar, a retractile spring connected at its rear end to said cross-bar and extending forwardly and upwardly therefrom and connected at its forward end to the underside of the seat, a forward cross member disposed under the forward portion of the seat, a leg fixed to and depending from said cross member, a longitudinally disposed rocker

foot at the lower end of said leg, a foot rod fixed on and extending at opposite sides of said rocker foot in front of the leg, and a hinge having a leaf opposed and connected to the underside of the forward portion of the seat and also having a pendent leaf opposed and connected to the forward side of said cross member. 5

WALTER J. WIECZOREK.
